UNITED STATES PATENT OFFICE.

WILLARD IRVING TWOMBLY, OF NEW YORK, N. Y., ASSIGNOR TO TWOMBLY MOTORS COMPANY, OF NEW YORK, N. Y., A CORPORATION OF NEW YORK.

GAS-ENGINE.

1,179,055.

Specification of Letters Patent. Patented Apr. 11, 1916.

Application filed June 21, 1912. Serial No. 704,973.

To all whom it may concern:

Be it known that I, WILLARD IRVING TWOMBLY, a citizen of the United States, residing in the borough of Manhattan, in 5 the city, county, and State of New York, have invented new and useful Improvements in Gas-Engines, of which the following is a specification.

This invention relates to internal combustion engines of the type in which a series of radially projecting cylinders rotate about a fixed crank shaft, although it will be obvious that it is also applicable to engines of other types.

15 It is the object of the invention to provide means to muffle the burnt gases as they are exhausted from the cylinders, and to provide adjustable means whereby instead of muffling the burnt gases to permit them to 20 be exhausted directly to the atmosphere, or to permit a portion of the gases to be exhausted directly to the atmosphere and to muffle a portion of such gases.

In the drawings accompanying and forming 25 a part of this specification, Figure 1 is a front elevation of a rotary cylinder engine, partly in section, illustrating an embodiment of my invention. Fig. 2 is an enlarged front elevation of a portion of my 30 improved means to muffle the exhaust from the cylinders. Fig. 3 is an enlarged plan view looking at the top of one of the cylinders illustrating the means to permit the exhaust of the burnt gases from the cylinders directly to the atmosphere. Fig. 4 is 35 an enlarged sectional side elevation of the head of a cylinder with my improvements applied thereto. Figs. 5 and 6 are plan and perspective views, respectively, of the adjustable means to permit the exhaust of 40 the burnt gases from the cylinders directly to the atmosphere; and Fig. 7 is an enlarged sectional end elevation of the means to muffle the exhaust of the burnt gases from 45 the cylinders.

Similar characters of reference designate like parts throughout the different views of the drawings.

In the drawings I have illustrated an embodiment of my invention in connection with a rotary engine comprising seven radially projecting cylinders 8 fixed to a casing 9 rotatably mounted on a hollow crank shaft, the charge of fuel being drawn into the

casing through the hollow crank shaft and 55 the charge of fuel to the cylinders controlled by mechanically operated valves in the piston, (not shown,) substantially as illustrated and described in my co-pending application filed September 19, 1911, Serial 60 No. 650,194, to which reference may be had for a more clear understanding of the same.

The exhaust of the burnt gases from the cylinders is controlled by valves 10 seated in removable valve seats or cages 11 screw 65 threaded into openings in the heads of the cylinders with the stems 12 slidably supported in a central sleeve or boss 13 of the valve cages. The opening and closing of the valves is controlled by a cam 14 on 70 the crank shaft through pusher rods 15 connected at one end to cam-followers or shoes 16, said rods pivotally connected at the other end, as at 16', to one end of rockers 17, the other forked end 18 of the rockers 75 engaging between collars 19, 19, on the end of the valve stems; springs 20 normally maintain the valves closed.

In this type of engine as heretofore constructed, it is the usual custom to exhaust 80 the burnt gases from the cylinders directly to the atmosphere. However, as is well known, this type of engine is extensively used as the motive power in aeroplanes in connection with aerial navigation, and 85 should a rich gas mixture be used and the engine rotate at a high velocity there is not a complete combustion of the gases in the cylinders before the exhaust takes place with the result that a flame shoots out through 90 the exhaust ports often resulting disastrously owing to the structure of the aeroplane taking fire from said flame from the exhaust. Furthermore, the noise of the exhaust from the cylinders is very objectionable. 95 To overcome these disadvantages I provide a muffler in the form of an annular chamber (designated in a general way by M) encircling or circumferentially extending around the heads of the cylinders, said 100 chamber being connected and common to all of the cylinders and rotatable therewith. In the present instance said chamber comprises a pair of axially separable sections 21, 21, connected together by bolts or tie 105 rods 22, and when connected having a series of tubular or sleeve portions 23 extending radially therethrough, one for each cylin-

der and in line with the valve port of the cylinder and open at the outer ends, an annular flange portion 24 of the valve cages projecting beyond the ends of the cylinders 5 engaging in said tubular portions, thereby preventing any circumferential or axial displacement of the chamber M relative to the cylinders. The sleeve portions 23 have a series of ports or openings 25 in the walls 10 thereof to connect said portions and the cylinders with the chamber M, the latter chamber also having ports 26, 27 in the front and rear walls. The outer open ends of the tubular portions 23 are normally 15 closed by a pair of disks 28, 29 engaging in an annular seat 30 therein and having central openings for the passage of the valve cage boss 13. In operation as the valves are opened and the outer ends of the tubular 20 portions 23 are closed by the disks 28, 29, the burnt gases from the cylinders in a highly compressed state pass through the sleeve ports 25 into the chamber M, in which they are fully expanded and gradually ex- 25 pelled through the ports 26, 27. To facilitate the cooling of the chamber M it is provided with a plurality of fins or ribs 31.

To permit of the burnt gases from the cylinders to exhaust directly through the 30 tubular portions 23 to the atmosphere I provide the disks 28 with openings, in the present instance two diametrically opposite segmental apertures 32, 32, and fix said disks in the seat 30 in the chamber sleeves 23.

The disks 29 are also provided with diametrically opposite segmental openings 33 35 and rotatably supported in the seats 30, whereby they may be adjusted relatively to the disks 28 and locked in adjusted positions by clamping collars 34. Should it be desired to exhaust direct to the atmosphere the collars 34 are loosened and the disks 29, which are in the nature of shutters, adjusted by means of a finger piece 35 so that the 40 openings therein register with the openings in the disks 28 when the collars 34 are again tightened and the disks locked in position. Should it be desired to exhaust through the chamber M, the disks 29 are adjusted so that the 45 openings therein lie adjacent to the imperforated portions of the disks 28 entirely shutting off the egress of the exhaust through the sleeve portions 23 directly to the atmosphere. The disks 29 may also be 50 adjusted so that only a portion of the openings in the disks 28 are uncovered, thereby permitting only a portion of the high pressures of combustion to exhaust directly to the atmosphere and a portion through the 55 chamber M.

Variations may be resorted to within the scope of my invention, and portions of the improvements may be used without others.

Having thus described my invention, I 60 claim:

1. In an internal combustion engine, the combination with a cylinder having an exhaust port in the head thereof, of a chamber connected to the exhaust port of the cylinder having outlet ports to exhaust the burnt 70 gases from the cylinder through said chamber; and means in said chamber in line with the exhaust port in the cylinder to permit the burnt gases to exhaust from the cylinder directly to the atmosphere or through the 75 ports in said chamber.

2. In an internal combustion engine, the combination with a cylinder having an exhaust port in the head thereof, of a chamber connected to the exhaust port of the cylinder having outlet ports to exhaust the burnt gases from the cylinder through said chamber; an outlet in the chamber in line with the exhaust port of the cylinder to permit the exhaust of the burnt gases from the cylinder directly to the atmosphere; and means to open and close said outlet to permit the burnt gases from the cylinder to exhaust directly through the port in the chamber in line with the exhaust port of the 80 cylinder or through the ports in the chamber. 85

3. In an internal combustion engine, the combination with a cylinder having a valve-controlled exhaust port in the head 90 thereof, of a chamber connected to the exhaust port of the cylinder having outlet ports to exhaust the burnt gases from the cylinder through said chamber; an outlet in the chamber concentric with the exhaust port in the cylinder to permit the exhaust of the burnt gases from the cylinder directly to the atmosphere; and a shutter to open and close said outlet to permit the burnt 95 gases to exhaust from the cylinder through said outlet directly to the atmosphere or through the chamber and chamber ports, or to regulate the size of said outlet to permit a portion of the burnt gases from the cylinder to exhaust through said outlet and a portion through the chamber. 100

4. In an internal combustion engine, the combination with a series of radially projecting and rotatable cylinders having exhaust ports in the heads thereof, of an annular chamber connected to and rotatable with the cylinders and with which the exhaust ports of the cylinders communicate, said chamber extending around the ends of the cylinders and comprising a pair of axially separable sections having circumferentially disposed cooling fins; and ports in the front and rear walls of said chambers at all times open to the atmosphere whereby to exhaust the burnt gases from the cylinders through said chamber. 115

5. In an internal combustion engine, the combination with a series of radially projecting and rotatable cylinders having exhaust ports in the heads thereof, of an an- 120

nular chamber connected to and rotatable with said cylinders and with which the exhaust ports communicate; openings in the front and rear walls of said chambers whereby to exhaust the burnt gases from the cylinders through said chamber; and adjustable openings in the peripheral wall of said chamber concentric with the exhaust ports of the cylinders whereby to permit the exhaust of the burnt gases of the cylinders directly to the atmosphere.

6. In an internal combustion engine, the combination with a series of radially projecting and rotatable cylinders having valve controlled exhaust ports in the heads thereof, of an annular chamber connected to the heads of and rotatable with the cylinders; openings in said chamber with which the exhaust ports in the cylinders communicate; ports in the front and rear walls of said chamber whereby to exhaust the burnt gases from the cylinder through said chamber; openings in the peripheral walls of the chambers concentric with the exhaust ports and adjustable means to open and close said openings whereby to permit the exhaust of the gases from the cylinders direct to the atmosphere through said openings or through the ports in the front and rear of the annular chamber.

7. In an internal combustion engine, the combination with a series of radially projecting and rotatable cylinders having valve controlled exhaust ports in the heads thereof, of an annular chamber connected to the heads of and rotatable with the cylinders; openings in said chamber with which the exhaust ports in the cylinders communicate; openings in the front and rear walls of said chamber whereby to exhaust the burnt gases from the cylinder through said chamber; openings in the peripheral walls of the chamber concentric with the exhaust ports to permit the exhaust of the burnt gases from the cylinders directly to the atmosphere; and adjustable means to open and close each of said openings whereby to permit the exhaust of the gases from the cylinders direct to the atmosphere or through the annular chamber, comprising a pair of disks having openings therein, one of said disks being fixed and the other adjustable whereby the openings in the adjustable disk may be caused to register with the openings in the fixed disk.

8. In an internal combustion engine, the combination with a series of radially projecting and rotatable cylinders having valve controlled exhaust ports in the heads thereof, of an annular chamber connected to the heads of and rotatable with the cylinders; openings in said chamber with which the exhaust ports in the cylinders communicate; ports in the front and rear walls of said chamber whereby to exhaust the burnt gases

from the cylinder through said chamber and chamber ports; openings in the peripheral walls of the chamber concentric with the exhaust ports in the cylinder; and adjustable means to open and close each of said openings whereby to permit the exhaust of the gases from the cylinders direct to the atmosphere through said openings or through the ports in the front and rear walls of the annular chamber, comprising a pair of disks having openings therein, one of said disks being fixed and the other adjustable whereby the openings in the adjustable disk may be caused to register with the openings in the fixed disk; and means to lock the adjustable disk in its adjusted positions.

9. In an internal combustion engine, the combination with a series of radially projecting and rotatable cylinders having exhaust ports in the heads thereof, of removable valve seats in said ports having annular flanges to project beyond the ends of the cylinders; an annular chamber to encircle the ends of the cylinders and having annular openings in which the annular flanges of the valve seats engage; and outlet ports in said annular chamber whereby to exhaust the burnt gases from the cylinders through said chamber.

10. In an internal combustion engine, the combination with a series of radially projecting and rotatable cylinders having exhaust ports in the heads thereof, of removable valve seats in said exhaust ports having annular flange portions to project beyond the cylinder heads; an annular chamber to encircle the heads of the cylinders, comprising a pair of axially separable sections; sleeve portions extending radially through said chamber in which the seat flanges engage to prevent axial and circumferential displacement of said chamber relative to the cylinders; inlet ports leading from said sleeve portions to the chamber; and outlet ports in the chamber whereby to exhaust the burnt gases from the cylinders through the chamber.

11. In an internal combustion engine, the combination with a series of radially projecting and rotatable cylinders having exhaust ports in the heads thereof, of removable valve seats in said ports having annular flanges to project beyond the ends of the cylinders and having central bosses or sleeves; valves seated in said seats with the valve stems slidably engaging in the seat bosses; an annular chamber to encircle the heads of the cylinders and having annular sleeve portions extending radially through said chamber in which the flanges of the valve seats engage; inlet ports leading from the sleeve portions to the chamber; outlet ports in said chamber whereby to exhaust the burnt gases from the cylinders through said chamber; and adjustable means in the

opposite ends of the sleeve portion to permit the exhaust of the burnt gases from the cylinders direct to the atmosphere.

12. In an internal combustion engine, the combination with a series of radially projecting and rotatable cylinders having exhaust ports in the heads thereof, of removable valve seats in said ports having annular flanges to project beyond the ends of the 10 cylinders and having central bosses or sleeves; valves seated in said seats with the valve stems slidably engaging in the seat bosses; an annular chamber to encircle the heads of the cylinders and having sleeve portions extending radially through said chamber in 15 which the flanges of the valve seats engage; inlet ports leading from the annular sleeve portions to the chamber; outlet ports in said

chamber whereby to exhaust the burnt gases from the cylinders through said chamber; 20 adjustable means in the opposite ends of the sleeve portions to permit the exhaust of the burnt gases from the cylinders direct to the atmosphere, comprising fixed disks having diametrically opposite segmental openings, 25 and rotatable disks having diametrically opposite segmental openings and adapted to be adjusted so that the openings therein register with the openings in the fixed disks; and means to lock the rotatable disks in adjusted positions.

WILLARD IRVING TWOMBLY.
